UNITED STATES PATENT OFFICE.

POWEL CROSLEY, JR., OF CINCINNATI, OHIO.

EXPLOSIVE-ENGINE STARTER.

1,302,637.

Specification of Letters Patent.

Patented May 6, 1919.

Application filed June 18, 1918. Serial No. 240,649.

To all whom it may concern:

Be it known that I, POWEL CROSLEY, Jr., a citizen of the United States, and a resident of Cincinnati, in the county of Hamilton 5 and State of Ohio, have invented certain new and useful Improvements in Explosive-Engine Starters, of which the following is a specification.

My invention relates to starting devices 10 for explosive or internal combustion engines and especially those used on automobiles.

The object of my invention is to provide a more reliable, efficient and durable device 15 of this character which will be simple in construction and operation and readily manufactured and installed.

In the drawing:

Figure 1 is a front elevation of part of 20 an automobile frame and a device embodying my invention installed thereon, the dotted lines indicating different positions of some of the parts.

Fig. 2 is a plan view of the device enlarged and with part of the manipulating 25 means omitted; and

Fig. 3 is a vertical cross-section on a plane 30 corresponding to the line 3—3 of Fig. 2, the ratchet being shown in full view and the dotted lines indicating different positions of some of the parts.

The shaft 1 will be understood to be that of an explosive engine not shown, which will be suitably supported on the frame 2 of the motor vehicle and which frame in a 35 large proportion of the motor vehicles now manufactured has at opposite sides of the shaft 1 upwardly projecting parts 3 which are fixed to the frame and help to support part of the mechanism in a manner which 40 need not be more fully described herein.

It will of course, be understood that to start the engine it is necessary to give the shaft 1 a partial rotation to the right; and this is usually done by applying a crank to 45 the engine shaft by means of a suitable clutch member 4 on its end and which is fastened along with the pulley 5, to the shaft 1 by means of a pin 6, passing through the pulley 5 from one periphery to the other, 50 and through the sleeve 7 of the clutch 4 and through the shaft 1 some distance away from the end of the shaft; the sleeve 7 being elongated for this purpose. I do not eliminate the clutch 4 because with the best devised

starters there may be occasion when the 55 crank will be necessary.

Integral with the sleeve 7 of the clutch member 4 is the ratchet wheel 8 about midway between the end of the shaft 1 and the pulley 5. A main arm 9 has a hollow hub 60 10 surrounding the ratchet wheel 8 and bearing on the sleeve 7 between the ratchet wheel 8 and the pulley 5. The front side of the hollow hub 10 has its opening large enough to admit the ratchet wheel 8 and a bushing 65 11 is fitted in this opening around the clutch member 4 and forms a bearing therefor. This bushing 11 is fixed in the front part of the hub by means of a screw 12 passing through the hub into the bushing. This 70 screw 12 also fixes to the outside of the hub one end of a tension helical spring 13 which extends some distance to the left and has its other end 14 fixed to the frame 2. This spring thus stretched between these two 75 points normally holds the arm 9 down at the left of the shaft 1 against the upward extension 3 of the frame.

The arm 9 is hollow throughout its length; its interior cavity being continuous with the 80 interior of the hollow hub 10 with which the arm 9 is integral. Inside this cavity of the arm 9 is the pawl 15 which is pivoted to swing up and down in the cavity by means of a pin 16 passing transversely through the 85 walls of the hollow arm and through this pawl some distance to the left of the ratchet wheel 8; the pawl inclining upwardly to the right to engage with the teeth of the ratchet wheel near the top of said wheel 90 within the cavity of the hub 10. The inner walls of the continuous cavities of the hub 10 and arm 9 are preferably finished smooth and the sides of the ratchet teeth and of the pawl fit against them snugly. The bushing 95 11 bears in the same way against the front sides of the ratchet teeth. Thus the arm is guided by the sides of the ratchet teeth in its swinging on the sleeve 7 and the pawl 15 is guided for up and down swinging for 100 engagement in or disengagement from the teeth of the ratchet wheel.

The lower side of the arm 9 is entirely open throughout the extent of its cavity and the opening extends part of the way around the hub 10. In this opening is located a dog 105 17 which as here shown is pivoted to swing up and down below the pawl 15 by means

of a pin 18, passing transversely through the walls of the hub 10, and through the right hand lower end part of the dog 17 somewhat below and to the left of the shaft 1 where the dog extends into the open part of the hub 10 at that side. From this pivot 18 the dog 17 extends slightly downwardly thus forming a lug 19 to engage with the end wall 20 of the opening in which the 10 dog lies and thus limiting the downward swinging of the dog. From the pivot 18 the dog extends upwardly and to the left, and then curves rather abruptly to the left and slightly downwardly. It extends in this 15 direction some distance past the pivot 16 of the pawl 15 and then abruptly turns slightly upwardly and to the left. It extends sufficiently far to the left to engage with the upward extension 3 of 20 the frame of the automobile on which the device is installed. The pawl 15 extends a short distance to the left from its pivot 16. This pawl is preferably a simple straight piece of metal with its right hand end 25 preferably shaped to engage with the ratchet wheel. Also these teeth of the ratchet wheel are preferably inclined away from the pawl so that there is no marked tendency to hold the pawl in engagement with the teeth as 30 where the teeth are under-cut as is usual in many ratchet wheels.

Where the dog 17 extends downwardly and to the left under the pawl 15, it has its upper side straight and is so proportioned 35 that this straight upper side will receive the straight lower side of the pawl 15 for some distance to the right and left of the pawl pivot 16 as is clearly shown by the full lines in Fig. 3. The left hand extension of the 40 pawl 15 does not extend farther to the left than the abrupt upward turn of the dog 17 before mentioned. The parts are so proportioned that when the pawl 15 is thus resting on this part of the dog, and the dog 45 is resting on the extension 3 of the frame along with the arm 9, the right hand end of the pawl 15 will be raised away from the teeth of the ratchet wheel 8.

Above the pawl 15, near its right hand end 50 is located a gripper 21 which as here shown consists of a piece of resilient wire, preferably piano wire, bent to U-shape and having the upper ends of the U bent in toward each other. The walls of the arm 9, near their 55 upper edges, have transversely through them openings 22 and, farther out, lateral lugs 23, and this gripper 21 is placed in position by spreading its legs and slipping them under the lugs 23 while the inturned 60 parts of their upper ends pass in through the openings 22. These inturned parts are long enough to project slightly inward past the inner walls of the arm cavity and if the pawl 15 rises far enough it will be caught 65 between these inturned parts and held up.

The extreme left end of the arm has an upward extension 24 of channel shape, preferably continuous with the hollow interior of the arm and approximately concentric with the shaft 1, forming in effect, part of 70 the periphery of a relatively very large sheave. Transversely through the side walls and the bottom of this upward extension is a pin 25 to which is connected the chain 26 which passes through the channeled upward 75 extension 24.

On the side frame bar 27 of the automobile to the right is fixed a bracket 28 which has upper and lower inwardly extending bearings 29 and 30 for an upright shaft 31, 80 on which is journaled a stepped sheave 32, comprising, concentrically attached together, an upper part 33 of greater diameter and a lower part 34 of lesser diameter; the upper part preferably being about 85 thrice the diameter of the lower part. The chain 26, passing upwardly and to the right from the arm-extension 24, is connected to the lower part of the sheave 32 by suitable means 35 near the 90 lower flange thereof, in such a manner that if the sheave be turned to the left the chain 26 will be wound up thereon and pull the arm 9 and attached mechanism over to the right. Another chain 36 is wound on the 95 upper larger part 33 of the sheave 32 in such a direction that its unwinding will turn the sheave 32 to the left and wind up the chain 36 as just mentioned. This chain 36, it will be understood, extends back in the automobile within easy reach of the driver's seat; and as is usual in devices of this character that end of the chain is provided with a suitable handle not shown herein. Usually 100 the chain extends through an opening in the dash board of the vehicle. The stepped sheave 32 is inclined forwardly and inwardly in such a manner as to receive both chains 26 and 36.

When the chain 36 is pulled back at a 110 given speed it pulls the arm 9 over to the right at about half that speed owing to the arrangement of the stepped pulley 32 which winds on the chain 26 only about half as fast as the chain 36 unwinds. As a consequence 115 of this the operator has a mechanical advantage of about two to one in overcoming the resistance at the left end of the arm 9, which resistance of course, is caused by the inertia, friction and compression in the engine that 120 is to be started, in addition of course to the resistance of the spring 13.

The upward extension 24 on the arm affords a greater turning moment initially 125 than if the chain 26 were merely connected directly to the main part of the arm without running up over this extension. It will, of course, be understood that the length of the arm will be such in any given installation as to avoid interference with the maximum 130

swinging of the arm to the right, by any objects on the automobile being engaged by this extension 24. Where such provision is made this extension, which may be integral with the main part of the arm, is much simpler than the articulated or rotary connections provided in this part of starting devices as heretofore constructed.

As soon as the arm 9 begins to leave the extension 3 on which it has been resting, the dog 17 which has also been resting on this extension 3 will drop down away from the pawl 15. Then the right hand end of the pawl 15 will drop into engagement with the teeth of the ratchet wheel 8, causing the shaft 1 to turn to the right along with the arm 9 as indicated by the dotted lines in Fig. 3. When this turning to the right has continued to about the position indicated by the dotted lines in Fig. 1 an explosion usually will have occurred in the engine and the engine will start with its rapid rotation of the shaft 1 and, of course, of the ratchet wheel 8. This causes violent impact of the teeth of the ratchet wheel with the pawl which has been engaging one of said teeth in the starting operation. This impact will be sufficient to throw the pawl 15 up between the inturned members of the gripper 21 which will then clutch the pawl and hold it away from the ratchet wheel, as shown by dotted lines in Fig. 1, during the return movement of the arm 9 to the left under the action of the spring 13 when the tension on the chains 36 and 26 has been released.

Now when the arm 9 comes down again on the extension 3 of the frame, the dog 17 engaging with this extension will be raised and by engagement with the left hand extension of the pawl 15 will bring it down away from the gripper 21 so that it again occupies an intermediate or neutral position indicated in full lines in Fig. 3; when it is ready to again engage with the ratchet wheel 8 as soon as the arm 9 is raised again, either for the next starting of the engine or for a repetition of the operation just described should the engine not start at the first operation.

Should the engine "back fire" during the operation of the starting device, causing the arm 9 to be violently rotated to the left by the engagement of its pawl 15 in the teeth of the ratchet wheel 8, this pawl will be released instantly upon the engagement of the dog 17 with the extension 3 and before the arm 9 engages with said extension; since the dog projects some distance below the lower side of the arm during the starting operation as shown by the dotted lines in the upper part of Fig. 3. This release of the pawl by the dog 17 is due to the engagement of the dog with the lower side of the pawl, between the pawl pivot 16 and the ratchet wheel; whereas the release of the

pawl 15 from the gripper 21 upon a normal return of the arm 9 to its initial position is caused by the engagement of the dog 17 with part of the pawl 15 to the left of the pivot 16.

Many automobiles do not have the upward extension 3 so far away from the shaft 1 as just described, but have an extension in about the position of the extension 3' indicated by dotted lines in Fig. 3. It will be seen that the dog 17, in its abrupt curvature to the left and extending upwardly from its pivot 18 close to the hub 10 adapts this dog for coöperation with the extension 3', as well as with the extension 3. In either case the dog will be swung upwardly in the arm by engagement with the extension 3 or 3', and cause the release of the pawl 15 either from the ratchet teeth or from the gripper, accordingly as it is in engagement with one or the other upon the return of the arm 9 to initial position. By this peculiar construction of the dog 17 my improved starting device operates with equal efficiency upon either kind of automobiles.

Moreover, by this combination and arrangement in which the dog is confined entirely below the pawl, without the necessity of engaging with the upper side of the pawl during any part of the operation, I am enabled to avoid undesirable increase in the depth of the mechanism in the plane of its swinging with the result that a somewhat greater range of swinging is permitted within the limited space allowed for it in the automobiles, as they are usually constructed.

It will be understood that the pulley 5 carries the belt which drives the fan for cooling the radiator of the engine. Usually the mechanism including the arm and its chain 26 will extend across between this belt and the fan blades. The compact and self contained arrangement of the arm and its operating mechanism greatly facilitates the relative positioning of the parts to the other parts of the automobile, such as this belt and this fan, so that none of the parts will interfere with others.

The gripper 21 holding the pawl 15 away from the rapidly rotating ratchet wheel 8 during the return of the arm 9, after the engine has been started, prevents noise and wear of the teeth and the pawl that would be otherwise occasioned. However, this holding of the pawl 15 away from the ratchet wheel 8 in no degree reduces the reliability of the device because the dog 17 will always release the pawl from the gripper, when the arm 9 returns to initial position, and when the dog by this releasing movement also comes into position to hold the pawl away from the ratchet wheel so that the function of the gripper 21 is no longer needed. And the dog 17 while thus holding the pawl 15 out of engaging,

noise-making and wearing position is ready to permit the pawl 15 to engage with the ratchet wheel whenever the engine is stopped and this position is needed and where the 5 wear and noise will not occur. Should the starting device be manipulated while the engine is running, the pawl 15 will immediately be thrown up into the gripper 21 where it will be held until the arm is brought 10 back to initial position, causing the dog 17 to act as has been described.

It will be seen therefore, that my improved starting apparatus is not only simple and compact in its construction but is simple and reliable in its operation and well adapted to remain in correct operating condition due to this simplicity and the prevention of unnecessary wear of its parts. The operative connection between the arm 9 and the ratchet 15 wheel 8 being positive, the device is adapted to retain its operativeness for an indefinite period; yet by providing for certain release of the pawl from the ratchet either upon normal starting or upon "back 20 firing" there is a sure avoidance of injury either to the operator or any part of the mechanism.

While certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. In an explosive-engine starter, in combination with the shaft of the engine, a toothed ratchet wheel rotating with said shaft, an arm swinging around said shaft, a pawl, a pivot for said pawl on said arm from which said pawl projects toward said ratchet wheel, a dog pivotally connected to 40 said arm and adapted to engage with a stationary part of the automobile when said arm is in initial position, and to engage with said pawl and hold it away from said ratchet wheel and to prevent material movement of said pawl either toward or away from said ratchet wheel, said dog releasing said pawl to swing either toward or away from said wheel when said arm is swung around said shaft, and means for swinging 45 said arm around said shaft.

2. In an explosive-engine starter, in combination with the shaft of the engine, a toothed ratchet wheel rotating with said shaft, an arm swinging around said shaft, a pawl, a pivot for said pawl on said arm, from which pivot said pawl projects toward 50 said ratchet wheel and also projects away from said ratchet wheel, means on said arm to make retaining contact with said pawl 55 when said pawl is thrown away from said

ratchet wheel by impact of the ratchet teeth, a dog pivotally connected to said arm and adapted to engage with a stationary part of the automobile when said arm is in initial position and to thereupon engage with said pawl at opposite sides of said pivot of said pawl and hold it away from said means and said ratchet wheel, said dog releasing said pawl either to engage with said ratchet wheel or to be thrown into contact with said 70 means by said wheel when said arm is swung around said shaft, and means for swinging said arm around said shaft.

3. In an explosive-engine starter, in combination with the shaft of the engine, a toothed ratchet wheel rotating with said shaft and comprising a sleeve projecting in both directions from said ratchet wheel along said shaft, a hollow arm and hollow hub integral with each other, said hub surrounding and bearing upon said sleeve at one side of said ratchet wheel and inclosing said ratchet wheel and having an opening surrounding said sleeve at the other side of said ratchet wheel and of diameter to 80 admit said ratchet wheel to the hollow interior of the hub, a bushing fixed to said hub within said opening and surrounding and bearing on this part of the sleeve, the interior of said hollow arm being continuous 85 with the interior of said hollow hub, a pawl pivoted in said hollow arm and adapted to engage with said ratchet wheel, means on said arm for controlling the position of said pawl relative to said ratchet wheel, and means for swinging said arm around said 90 shaft and sleeve.

4. In an explosive-engine starter, in combination with the shaft of the engine, a toothed ratchet wheel rotating with said shaft, an arm swinging around said shaft, a pawl consisting substantially of a piece of material with its upper and lower sides and its lateral sides, respectively, substantially parallel, a pivot extending transversely through said 105 pawl near one end thereof and permitting said pawl to swing into engagement with the teeth of said ratchet wheel in a position upwardly inclined from said pivot toward said ratchet wheel, a dog pivotally connected 110 to said arm near one of the ends of said dog, and having an upper side inclined to lie against the lower side of said pawl and hold said pawl away from said ratchet wheel, said dog being so shaped on its lower side that it 115 will engage with a stationary part of the automobile whether said part be in one or the other of various positions and by said engagement being brought into the just described relative position to said pawl, and 120 means for swinging said arm around said shaft.

5. In an explosive-engine starter, in combination with the shaft of the engine, a toothed ratchet wheel rotating with said shaft, an 125

- arm swinging around said shaft, a pawl, a pivot on said arm extending transversely through said pawl and permitting said pawl to swing into engagement with the teeth of 5 said ratchet wheel in a position upwardly inclined from said pivot toward said ratchet wheel, a dog pivotally connected to said arm near one of the ends of said dog, and engaging with the lower side of said pawl at 10 one side of said pivot, to the exclusion of any engagement of said dog with the upper side of said pawl during any part of the operation of said starter, said dog being adapted to engage its lower side with a stationary 15 part of the apparatus and thereby position said pawl a desired distance from said ratchet wheel, and means for swinging said arm around said shaft.
6. In an explosive-engine starter, in combination with the shaft of the engine, a toothed ratchet wheel rotating with said shaft, an arm swinging around said shaft, a pawl, a pivot on said arm extending transversely through said pawl and permitting said pawl 20 to swing into engagement with the teeth of said ratchet wheel in a position upwardly inclined from said pivot toward said ratchet wheel, a dog pivotally connected to said arm near one of the ends of said dog, and engaging with the lower side of said pawl at 25 both sides of said pivot, to the exclusion of any engagement of said dog with the upper side of said pawl during any part of the operation of said starter, said dog being adapted to engage its lower side with a stationary 30 part of the apparatus and thereby position said pawl a desired distance from said ratchet wheel, and means for swinging said arm around said shaft.
- 35 7. In an explosive-engine starter, in combination with the shaft of the engine, a toothed ratchet wheel rotating with said shaft, an arm and hub having parts flanking said ratchet wheel, a pawl pivotally mounted between the flanking parts of said arm and adapted to engage with the teeth of said ratchet wheel, a gripper consisting of a 40 piece of resilient material bent into substantially U-shape with the upper end parts of the legs turned in toward each other, said arm having openings in its walls above said pawl and these inturned parts of said gripper projecting in through said openings and being adapted to grip said pawl when it is thrown away from said ratchet wheel by impact with the teeth thereof during rapid rotation, means to bring said pawl to a position intermediate of said gripper and the teeth of said ratchet wheel when said arm assumes an initial position, means for swinging said arm out of said position, and means for returning said arm to said position. 45
8. In an explosive-engine starter, in combination with the shaft of the engine, a toothed ratchet wheel rotating with said shaft, an arm and hub having parts flanking said ratchet wheel, a pawl pivotally mounted between the flanking parts of said arm and adapted to engage with the teeth of said ratchet wheel, a gripper consisting of a piece 50 of resilient material bent into substantially U-shape with the upper end parts of the legs turned in toward each other, said arm having openings in its walls above said pawl and these inturned parts of said gripper projecting in through said openings and being adapted to grip said pawl when it is thrown away from said ratchet wheel by impact with the teeth thereof during rapid rotation, means to bring said pawl to a position intermediate of said gripper and the teeth of said ratchet wheel when said arm assumes an initial position, means for swinging said arm out of said position, and means for returning said arm to said position. 55
9. In an explosive-engine starter, in combination with the shaft of the engine, a toothed ratchet wheel rotating with said shaft, an arm and hub having parts flanking said ratchet wheel, a pawl pivotally mounted between the flanking parts of said arm and adapted to engage with the teeth of said ratchet wheel, a gripper consisting of a piece 60 of resilient material bent into substantially U-shape with the upper end parts of the legs turned in toward each other, said arm having openings in its walls above said pawl and these inturned parts of said gripper projecting in through said openings and being adapted to grip said pawl when it is thrown away from said ratchet wheel by impact with the teeth thereof during rapid rotation, means to bring said pawl to a position intermediate of said gripper and the teeth of said ratchet wheel when said arm assumes an initial position, means for swinging said arm out of said position, and means for returning said arm to said position. 65
10. In an explosive-engine starter, in combination with the shaft of the engine, a toothed ratchet wheel rotating with said shaft, an arm and hub having parts flanking said ratchet wheel, a pawl pivotally mounted between the flanking parts of said arm and adapted to engage with the teeth of said ratchet wheel, a gripper consisting of a piece 70 of resilient material bent into substantially U-shape with the upper end parts of the legs turned in toward each other, said arm having openings in its walls above said pawl and these inturned parts of said gripper projecting in through said openings and being adapted to grip said pawl when it is thrown away from said ratchet wheel by impact with the teeth thereof during rapid rotation, means to bring said pawl to a position intermediate of said gripper and the teeth of said ratchet wheel when said arm assumes an initial position, means for swinging said arm out of said position, and means for returning said arm to said position. 75
11. In an explosive-engine starter, in combination with the shaft of the engine, a toothed ratchet wheel rotating with said shaft, an arm and hub having parts flanking said ratchet wheel, a pawl pivotally mounted between the flanking parts of said arm and adapted to engage with the teeth of said ratchet wheel, a gripper consisting of a piece 80 of resilient material bent into substantially U-shape with the upper end parts of the legs turned in toward each other, said arm having openings in its walls above said pawl and these inturned parts of said gripper projecting in through said openings and being adapted to grip said pawl when it is thrown away from said ratchet wheel by impact with the teeth thereof during rapid rotation, means to bring said pawl to a position intermediate of said gripper and the teeth of said ratchet wheel when said arm assumes an initial position, means for swinging said arm out of said position, and means for returning said arm to said position. 85
